UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

NAME DOBBY FOR LOOMS

Application filed November 12, 1928. Serial No. 318,915.

This invention relates to improvements in dobbies for looms more particularly designed for the weaving of names in selvages, etc., and it is the general object of the invention 5 to provide an improved form of auxiliary finger for use in a type of mechanism set forth in my co-pending application Ser. No. 246,953 filed January 16, 1928.

In the form of dobbi set forth in that application there is provided a set of auxiliary fingers which cooperate with a top pattern surface, said fingers being movable either to operative or inoperative position. When in the operative position each finger when depressed will act through a vertical rod to cause movement of the corresponding dobbi hook and when in inoperative position will be out of the range of action of the top or auxiliary pattern surface. I have found that in certain instances the weight of the auxiliary finger resting on the upright rods causes sluggishness in the return of the main dobbi fingers to their lower position, and it is accordingly an important object of my present invention so to form the auxiliary fingers that they will exert practically no force on the rods when in inoperative position or when in operative position but not acted upon by the upper pattern surface.

The auxiliary fingers as shown in my aforesaid application are mounted on a rod supported by arms which swing around a fixed pivot. The arcuate movement of the axes of the fingers results in a corresponding movement on that end of the finger which cooperates with the upright rods, and it is accordingly a further object of my present invention to form the auxiliary fingers so that they will compensate for the arcuate movement of their axes and act to hold their upright rod engaging portions in substantially the same horizontal position.

I have found also that said auxiliary fingers operate more efficiently when they have a flat upper pattern engaging surface and a grooved lower surface to cooperate with the aforesaid upright rods, and it is accordingly a more detailed object of my invention to provide a dobbi finger formed thus.

With these and other objects in view which

will appear as the description proceeds, my invention resides in the combination and arrangement of parts hereinafter described and set forth in the claims.

In the accompanying drawings, wherein a convenient embodiment of my invention is set forth,

Fig. 1 is a side elevation of enough of the dobbi shown in my aforesaid application to illustrate my present invention,

Fig. 2 is a detailed front elevation of two adjacent auxiliary fingers and their corresponding rods taken in the direction of arrow 2, Fig. 1,

Fig. 3 is a detailed top plan view taken in the direction of arrow 3, Fig. 1,

Fig. 4 is a side elevation of one of the auxiliary fingers, and

Fig. 5 is a top plan view of the finger shown in Fig. 4.

It is to be understood that the dobbi shown herein is capable of producing two weaves, one governed by the main pattern surface to weave a name, for instance, and the other controlled by the auxiliary pattern surface to weave the space between names. Control is passed from the main to the auxiliary and back to the main pattern surface by means set forth in my aforesaid application. As these means form no part of my present invention they are not described in detail.

Referring particularly to Fig. 1, I have shown a loom frame 10 to which are secured the dobbi plates or sides 11. A main pattern cylinder 12 is provided with a main pattern surface indicated at 13 and may be actuated by means of a ratchet 14. Said cylinder is supported on a shaft 15 rotatably mounted in the dobbi sides or frame and said cylinder may move around the axis of the shaft 15 under influence of a pull pawl 16 cooperating with the ratchet 14.

Lower or main dobbi fingers 17 are pivoted on a pin 18 and rise and fall under influence of the main pattern surface 13. Certain of said main dobbi fingers have upwardly inclined portions 19 while others have the substantially horizontal extensions 20. Said extensions 19 and 20 cooperate with

vertical lifter rods 21 which move through guides 22 and 23.

The harness levers 25 are pivotally mounted on jacks 26 which in turn move about a fixed pin 27 supported by the dobby frame. Each jack has pivoted thereto a dobby back lever 31 to which are pivoted upper and lower hooks 32 and 33, respectively. These hooks are controlled by the fingers and move into the path of a dobby knife K shown in dotted lines in Fig. 1, to effect lifting movement of the harness levers 25.

The auxiliary control for the rods 21 comprises a set of auxiliary fingers 70 which are pivoted as at 69 to a pair of spaced upright arms 67 which are pivoted about a fixed stud 68. Each of said auxiliary fingers is provided with an operative surface 71 and a supporting tail 72. Rigid with one arm 67 is a second arm A which has operative connection with a lever 60.

An upper pattern cylinder 50 has a pattern surface 51 provided with the usual dobby pegs 73, said cylinder rotating around the stud 53 by means of a ratchet 52 and pawl 54 when the latter is called into action.

In the operation of the matter thus far described it is to be understood that the auxiliary fingers 70 may move horizontally to the left from the position shown in Fig. 1 where the surfaces 71 will be out of the path of the auxiliary pattern chain. The connections whereby lever 60 is rocked to cause oscillation of the arm 67 are substantially the same as those shown in my aforesaid application. Certain other parts shown in the drawings are for the purpose of identifying the present disclosure with my previous application and form no part of my present invention.

As previously stated the fingers 70 have in practice shown a tendency to act by their weight to lift the main fingers 17 and therefore render the latter uncertain in their return to normal down position and it is an important object of my present invention to correct this tendency by counterweighting the levers 70 so that they will be ineffective to exert undesired downward strains on the upright rods 21. Accordingly, in carrying out my invention, I form the auxiliary fingers as shown in Figs. 4 and 5 with a bearing 80 through which the rod 69 may extend. The finger has a lower edge 81 which as shown in Fig. 2 is preferably concave so as to insure proper registry with the top of the wire 21. That portion of the finger which lies to the right of the bearing 80 as shown in Fig. 4 is preferably made as light as is consistent with requisite strength. There is extended to the left of the bearing a counterweight 82 of sufficient weight to hold the small end to the right normally in raised position.

In order to support the counterweights I provide a bar 83 which extends across the back of the dobby and has extended there-

through screws 84 which hold said bar to the dobby frame 11. Said bar extends above the top surface 85 of the frames and is preferably rounded so as to have contact with the lower edge of the counterweight at practically one point only. The lower edge of said counterweight as shown in Fig. 4 is preferably inclined downwardly and inwardly with respect to the outer end of the counterweight, said surface being indicated at 86 and resting on the bar 83.

As shown in Fig. 2 the operative end of the auxiliary finger is spaced slightly above the upper end of the rod 21 so as normally to exert no downward pressure whatever upon said rods. In this way the lower fingers 17 and therefore the indications given to the hooks 32 and 33 will be more accurate than is possible in the dobby set forth in my aforesaid application.

The purpose of forming the lower portion of the counterweight with the edge 86 as shown in Fig. 4 is to insure proper positioning of the edge 81 with respect to the rods 21. It will be noted that the rod 69 moves around stud 68 as a center so that the bearings 80 are lifted when the fingers move to the left from the position shown in Fig. 1. Under these conditions the right hand end of said fingers as viewed in the drawings would either be lifted into improper relation with respect to the pattern surface 51 or be depressed so as to exert pressure on the rods 21 unless said surface 86 were correctly formed. As set forth herein I form said surface so that the same extends in the same general direction as the path of movement of the axis or rod 69, thus holding the surface 81 in substantially the same horizontal plane. It is necessary, as a matter of fact, to have the surface 86 inclined downwardly slightly more than the path of movement of the rod 69. When there is sufficient clearance between the pegs 73 and the surface 71 of the auxiliary fingers it is not necessary to have the lower surface 86 of the counterweight as accurately made as shown to clear the path of movement of the rod 69.

It is to be understood that in operation the auxiliary fingers will be shifted into and out of operative relation with respect to the auxiliary pattern surface 51 and that when the fingers are in the position shown in Fig. 1 the pegs 73, when in their lowest position, will depress selected fingers 70 and raise the corresponding counterweights 82, thus acting through the rods 21 to lift the corresponding main fingers 17 and lower the associated hooks. When the mechanism operates to shift the control of weave from the upper surface 51 to the lower surface 13 there will be a corresponding movement to the left on the part of the auxiliary fingers and the surfaces 86 will slide over the upper edge of the bar 83 to maintain said fingers 70 in their

proper relation relatively to the auxiliary pattern surface and the upright rods 21.

A detailed feature of my invention relates to the method of forming the upper surface 71 of the finger 70 and by reference to Fig. 2 it will be seen that said surface is preferably smooth and flat so that the pegs 73 if not accurately aligned centrally with respect to the fingers 70 will nevertheless be able to effect depression of the latter. It will also be seen that a small vertical bar 88 may be cast to cooperate with the adjacent finger to reduce friction. A shallow hub 89 around the bearing 80 may also be provided for the same purpose.

From the foregoing it will be seen that I have provided a dobby mechanism with auxiliary fingers so constructed and controlled as to be normally out of contact with the upright rods except as such times as the latter are to be intentionally subjected to a downward pressure for the purpose of indicating the hooks. It will further be seen that the counterweights and the supporting bar are so formed that they cooperate with each other to keep the auxiliary hooks properly related with respect to the auxiliary pattern surface and the upright rods. Furthermore, it will be seen as a detailed feature of my invention that the upper surface 71 of the auxiliary fingers is preferably smooth although the lower edge 81 may be grooved to effect alignment and proper cooperation between the auxiliary fingers and the rods 21.

Having thus described my invention it will be seen that changes and modifications may be made therein by those skilled in the art without departing from the spirit and scope of the invention and I do not wish to be limited to the details herein disclosed, but what I claim is:

1. In a loom dobby, a pattern surface, a set of dobby fingers to cooperate with the pattern surface, a pivotal support for the fingers movable to present said fingers into operative and inoperative relationship with respect to the pattern surface, a control rod to be depressed by said fingers, a counterweight rigid with each finger, and a support for the counterweights tending to hold the latter normally out of contact with its corresponding control rod.

2. In a loom dobby, a movable pattern surface, a set of dobby fingers to cooperate with the surface, a movable support for said fingers about which the latter may move pivotally, control rods to cooperate with the fingers, a counterweight rigid with each finger and a support for the counterweights to engage the latter so that normally said fingers are spaced above the control rods.

3. In a loom dobby, a movable pattern surface, a set of dobby fingers to cooperate with the surface, a movable support for said

fingers about which the latter may move pivotally, control rods to cooperate with the fingers, a counterweight rigid with each finger, and a support for the counterweights to engage the latter so that normally said fingers are spaced above the control rods, said counterweight being provided with a lower surface which is inclined and adapted for continuous engagement with the support as the fingers move into and out of operative position with respect to the pattern surface, said inclined surface cooperating with the support to keep said fingers spaced above the rods as the fingers move toward and from operative position.

4. In a loom dobby, a movable pattern surface, a set of dobby fingers to cooperate with the surface, a movable support for said fingers about which the latter may move pivotally, control rods to cooperate with the fingers, a counterweight rigid with each finger, and a support for the counterweights to engage the latter so that normally said fingers are spaced above the control rods, the under surface of the counterweight being inclined in the same general direction as the path through which the pivotal support for the fingers moves and cooperating with the support to hold the fingers spaced above the control rods as the fingers move toward and from operative position relatively to the pattern surface.

5. In a loom dobby having a main set of dobby fingers and control rods extending upwardly therefrom, a pattern surface, a set of auxiliary fingers to cooperate with the pattern surface and having operative relation with the rods to control the position of the main dobby fingers, a pivotal support for the auxiliary fingers, said support being movable to carry the auxiliary fingers into and out of operative relation with respect to the auxiliary pattern surface, a counterweight formed integral with each auxiliary finger, and a support for all the counterweights to position the latter so that normally the auxiliary fingers are spaced slightly above the rods for all positions of the pivotal support for the auxiliary fingers.

6. In a loom dobby having a main set of dobby fingers and control rods extending upwardly therefrom, an auxiliary pattern surface, a set of auxiliary fingers to cooperate with the pattern surface and capable of having operative relation with the rods to control the position of the main dobby fingers, a pivotal support for the auxiliary fingers, said support being movable to carry the auxiliary fingers into and out of operative relation with respect to the auxiliary pattern surface, a counterweight formed integral with each auxiliary finger, and a support for all the counterweights to position the latter so that normally and during movement of the auxiliary fingers toward and from operative position

- relatively to the pattern surface the auxiliary fingers will be spaced slightly above the rods.
7. In a loom dobby having a main set of dobby fingers and control rods extending upwardly therefrom, an auxiliary pattern surface, a set of auxiliary fingers to cooperate with the pattern surface and capable of having operative relation with the rods to control the position of the main dobby fingers,
- 10 a pivotal support for the auxiliary fingers, said support being movable to carry the auxiliary fingers into and out of operative relation with respect to the auxiliary pattern surface, a counterweight for each auxiliary finger, a fixed support on which the counterweights may rest, each counterweight having on the under side thereof an inclined surface to have sliding contact with the support as the auxiliary fingers move toward and from operative position, said inclined surface cooperating with the support to keep the auxiliary fingers spaced normally above the rods as said fingers move toward and from operative position.
- 15 8. In a loom dobby having a main set of dobby fingers, rods extending upwardly from the fingers and movable longitudinally to cause movements of the main fingers, an auxiliary pattern chain having pattern indicating elements located above the rods, auxiliary fingers located between the auxiliary pattern surface and the rods, said fingers having their under portions provided with a longitudinal groove to have cooperation with the rods and
- 20 30 said fingers having flat upper surfaces to cooperate with the pattern elements, and a movable support for the fingers whereby the fingers are movable in a direction parallel to the grooves.
- 35 40 9. In a loom dobby having main dobby fingers, a set of rod elements extending upwardly from the fingers and movable longitudinally to effect movements of the fingers, an auxiliary pattern surface having a set of
- 45 50 pattern elements located above the rod elements, auxiliary dobby fingers located between the rod elements and the pattern chain elements, that portion of the auxiliary fingers adjacent one set of elements having a longitudinal groove to receive said one set of elements and that portion of the auxiliary fingers adjacent the other set of elements being flat, whereby said other set of elements may assume a plurality of positions laterally
- 55 60 with respect to the flat surface while the said one set of elements act to determine the lateral position of the auxiliary fingers, and a movable support for the fingers whereby the latter are movable in a direction parallel to the grooves.

In testimony whereof I have hereunto affixed my signature.

ALBERT A. GORDON.
